REFRIGERATING APPARATUS

Jesse G. King, Dayton, Ohio, assignor to Frigidaire Corporation, Dayton, Ohio, a corporation of Delaware

Application August 31, 1928, Serial No. 303,263
Renewed October 21, 1932

8 Claims. (Cl. 62—115)

This invention relates to refrigerating apparatus and particularly to soda fountains and similar devices in which various commodities of different characters are maintained at different temperatures.

It is one of the objects of the invention to provide a simplified and economical refrigerating system particularly adapted to soda fountains.

Another object of the invention is to provide an improved and simplified arrangement for maintaining a number of different temperatures by means of a single refrigerating system.

More specifically it is one of the objects of the invention to operate a plurality of evaporating elements in series and to provide an improved and simplified means for controlling the amount of liquid refrigerant which enters successive evaporators of the series.

Further objects and advantages of the present invention will be apparent from the following description, reference being had to the accompanying drawing, wherein a preferred form of the present invention is clearly shown.

In the drawing:

Fig. 1 is a diagram of a refrigerating system embodying the present invention; and

Fig. 2 is a vertical longitudinal section of a portion of a control device.

It is usual to provide soda fountains with a compartment for maintaining ice cream at a temperature, for example, of 7° F. or less, a compartment for cooling and maintaining water on draft at a temperature between 35° and 40° and a compartment commonly called a syrup rail for maintaining containers of fountain syrups, fruit juices and the like, at temperatures between 35° and 55° F.

My invention is concerned with an improved arrangement and method for maintaining the above mentioned compartments at their individual proper temperatures by means of a single refrigerating system or apparatus.

Referring to Fig. 1 any suitable soda fountain is provided with an ice cream storage compartment 11, a water cooling compartment 12 and a syrup rail or compartment 13 for holding syrup containers. Each of the compartments may be suitably insulated according to the temperature at which it is to be maintained. A relatively high pressure evaporator 16 is placed in the water compartment and a relatively low pressure evaporator 17 placed in the ice cream compartment. Preferably the evaporator 17 is immersed in a non-freezing solution such as brine as is usual in cases of this character, and the evapora-

tor 16 is immersed in fresh water, which may be either the water to be cooled, or a water bath, in which is immersed a heat exchanger such as 18, through which the water to be cooled is circulated. These evaporators are preferably of the flooded type and each includes a header 20 forming a reservoir for liquid refrigerant which is kept at a constant level therein under the control of a float 22, and refrigerant circulating tubes or coils 23. The evaporators are supplied with liquid refrigerant through liquid lines 26 and 27 connected in parallel to a condensing element generally denoted by 28 which also withdraws evaporated refrigerant from both said evaporators through a vapor conduit 29.

Refrigerant evaporated in the evaporator 16 is withdrawn through a conduit 30 which is ultimately connected to the conduit 29 and which is provided with any suitable pressure regulating shut-off valve 31, the construction of which may be, for example as is illustrated and described in the application of Ernest Dickey, Serial No. 753,048, filed December 1, 1924. This valve is opened by the pressure of refrigerant in the evaporator 16 and automatically closes at some predetermined low pressure corresponding, for example, to 25° F. and thus prevents refrigeration of the evaporator below that temperature.

The condensing element 28 includes any suitable compressor 32 actuated by a motor 33 under the control of a switch 34 which is operated in response to the pressure existing in the vapor conduit 29. When the pressure existing in this conduit is above that corresponding to a temperature of about 5° F. the switch closes to actuate the compressor and withdraw the refrigerant from the evaporator 17 until the pressure has been reduced to a value corresponding to a predetermined low temperature, for example —6° F. Refrigerant is evaporated in and withdrawn from evaporator 16 only when the pressure regulating valve 31 is open. Preferably the valve is arranged to snap open at a pressure corresponding to about 28° F., and to remain open until the pressure has been reduced to a value corresponding to an evaporator temperature of about 14° F. when the valve snaps closed.

This will cause a layer of ice to form about the evaporator 16, which may periodically increase and decrease in thickness in accordance with the cyclical variations in temperature of the evaporator and will serve to keep the circulating water at a more or less steady temperature of about 40°.

The conduit 30 connecting the evaporator 16

and the exhaust conduit 29 includes a portion 35 forming an evaporator which is in thermal relation with the syrup rail. The connection of the conduit 30 to the header 20 of evaporator 16 is so arranged that liquid refrigerant is supplied from the header to the evaporator 35 along with the vapor withdrawn. One way of arranging this connection is illustrated herein for the sake of example. The header 20 of evaporator 16 is provided with the usual head or end plate 40, secured to the header in any suitable manner, as by bolts passing through holes 41. The head 40 is provided with an inlet 42 and outlet 43 for connection to valves 44 and 45 in the liquid and vapor lines 15 27 and 30 respectively. Inside the head, and containing the liquid inlet passage 42 is a boss 46 having a small opening 47 for the admission of liquid to the header. A tubular support 48 for the float 22 and a needle valve 50 (controlled by 20 the float) is mounted on the boss 46, and is provided with a passage 51 registering with the opening 47 and forming a guide for the valve 50.

A suction tube 52 extends from the outlet 43 into the header, terminating in a horizontal opening 53 above the normal level of liquid in the header. The header normally contains liquid refrigerant to the level 54 and oil to the level 55. At the level 55 an oil drain hole 56 is pierced in the tube 52. This refrigerant vapor is withdrawn 30 through the tube 52 from above the liquid level, and oil may drain out of the header whenever it reaches the level 55. A small tube 57 connects with the passage 51 near the opening 47, and just back of the point of the valve 50. This tube terminates within the vapor tube 52. The tube 52 may have a constriction 58 at the end of the small tube 57, so that when vapor is withdrawn through the tube 52, suction will be produced, drawing liquid refrigerant through the tube 57 into the 40 tube 52. However, in many cases sufficient liquid will flow through the tube 57 without the use of the constriction 58. This will be readily understood when it is considered that liquid refrigerant in the inlet 42 is under relatively high pressure, for example 50 pounds per square inch, while the liquid in the header is under relatively low pressure, for example 9 pounds per square inch. Therefore whenever the float valve opens, liquid flows through the opening 47 and into the passage 51 at high velocity. The body of liquid present in the passage 51 tends to stop this rapid flow of liquid and to convert its velocity head into pressure head. This pressure-head is sufficient to cause a certain amount of liquid to flow up 50 through the tube 58 into tube 52. Therefore liquid refrigerant is drawn into the evaporator 35 along with the vapor, and is there evaporated, cooling the syrup rail.

It may happen that more liquid may be supplied to the evaporator 35 at certain times than can be evaporated. In order to prevent the undesirable result of liquid refrigerant entering the conduit 29 and compressor intake, the conduit 30, between the outlet of the evaporator 35 and the valve 31, passes through the water compartment. Preferably this portion of the conduit includes a heat exchanger in the form of a trap 60, immersed in the water adjacent the point 61 where the warm water flows into the compartment. The trap prevents liquid from flowing down directly to the compressor, and its heat exchange surface, in contact with the relatively warm water evaporates and superheats any liquid refrigerant flowing from the evaporator 35. Since this refrigerant is at a temperature of 25°

F. or less, it is readily evaporated and superheated by the water which is at a temperature of 40° F. or more.

The above described system provides a very simple and reliable method of cooling the syrup rail of a soda fountain and of controlling the amount of liquid refrigerant which is admitted to the syrup rail evaporator.

While the form of embodiment of the invention as herein disclosed, constitutes a preferred form, it is to be understood that other forms might be adopted, all coming within the scope of the claims which follow.

What is claimed follows:

1. A soda fountain comprising in combination an ice cream storage compartment, a water cooling compartment, a syrup compartment, an evaporator for cooling each of said compartments, the syrup compartment evaporator and water compartment evaporator being connected in series, a condensing element for supplying liquid refrigerant to the ice cream compartment evaporator and water compartment evaporator, and conduits for returning the evaporated refrigerant from the ice cream compartment evaporator and from the syrup compartment evaporator, the conduit from the syrup compartment evaporator passing through the water cooling compartment.

2. A soda fountain comprising in combination an ice cream storage compartment, a compartment for cooling circulating water including a water container, a syrup compartment, an evaporator for cooling each of said compartments, the water compartment evaporator being immersed in said container, a condensing element for supplying refrigerant to the evaporators and conduits for returning the evaporated refrigerant from the evaporators to the condensing element, the conduit from the syrup compartment evaporator having a portion immersed in said container adjacent the point of entry of the circulating water.

3. A soda fountain comprising in combination an ice cream storage compartment, a water cooling compartment, a syrup compartment, an evaporator for cooling each of said compartments, a condensing element for supplying refrigerant to the evaporators, and conduits for returning the evaporated refrigerant from the evaporators to the condensing element, the conduit from the syrup compartment evaporator including a liquid trap disposed in the water cooling compartment for evaporating liquid refrigerant flowing from the syrup rail compartment.

4. Refrigerating apparatus comprising in combination a pair of compartments to be cooled, an evaporator in each of the compartments, said evaporators being connected in series and arranged to deliver liquid refrigerant from the first evaporator to the second, a condensing element for supplying liquid refrigerant to the first evaporator and a conduit connecting the outlet of the second evaporator to the intake of the condensing element, said conduit including a heat exchanger disposed in the compartment containing the first evaporator for evaporating liquid refrigerant passing from the second evaporator.

5. Refrigerating apparatus comprising in combination a pair of compartments to be cooled, an evaporator in each of the compartments, said evaporators being connected in series and arranged to deliver liquid refrigerant from the first evaporator to the second, the second evaporator being above the first, a condensing element for supplying liquid refrigerant to the first evapora-

tor and a conduit connecting the outlet of the second evaporator to the intake of the condensing element, said conduit including a liquid trap disposed in heat exchange relation with the compartment containing the first evaporator.

6. A refrigerating apparatus comprising in combination, a compartment having an evaporator disposed therein, a second compartment also having an evaporator disposed therein, a refrigerant liquefying and circulating unit having a liquid refrigerant supply connection with the first named evaporator and a gaseous refrigerant connection with the second named evaporator, means for maintaining a predetermined quantity 15 of liquid refrigerant in said first named evaporator, a conduit extending from said first named compartment to said second named compartment and having one of its ends communicating with the first named evaporator above the level of 20 liquid refrigerant therein and having its other end connected with said second named evaporator, refrigerant conveying means having one end thereof disposed below the level of liquid refrigerant in said first named evaporator and 25 having its other end extending above the level of liquid refrigerant, a Venturi device within a portion of said conduit, the end of said refrigerant conveying means above the level of liquid refrigerant in said first named evaporator being associated 30 with said Venturi device, and said Venturi device being rendered effective by operations of said refrigerant liquefying and circulating unit for transferring liquid refrigerant from said first named evaporator to said second named evaporator.

7. A refrigerating apparatus comprising in combination, a compartment having an evaporator disposed therein, a second compartment also having an evaporator disposed therein and located above the evaporator in the first named compartment, a refrigerant liquefying and circulating unit having a liquid refrigerant supply connection with the first named evaporator and a gaseous refrigerant connection with the second 45 named evaporator, means for maintaining a predetermined quantity of liquid refrigerant in said first named evaporator, a conduit extending from said first named compartment to said second named compartment and having one of its ends communicating with the first named evaporator above the level of liquid refrigerant there-

in and having its other end connected with said second named evaporator, refrigerant conveying means having one end thereof disposed below the level of liquid refrigerant in said first named evaporator and having its other end extending 80 above the level of liquid refrigerant, a Venturi device within a portion of said conduit, the end of said refrigerant conveying means above the level of liquid refrigerant in said first named evaporator being associated with said Venturi device, and said Venturi device being rendered effective by operations of said refrigerant liquefying and circulating unit for lifting liquid refrigerant from said first named evaporator to

85 said second named evaporator.

8. A refrigerating apparatus comprising in combination, a compartment having an evaporator disposed therein, a second compartment also having an evaporator disposed therein and located above the evaporator in the first named compartment, a refrigerant liquefying and circulating unit having a liquid refrigerant supply connection with the first named evaporator and a gaseous refrigerant connection with the second 90 named evaporator, a float valve mechanism for maintaining a predetermined quantity of liquid refrigerant in said first named evaporator, a conduit extending from said first named compartment to said second named compartment and having one of its ends communicating with the first named evaporator above the level of liquid refrigerant therein and having its other end connected with said second named evaporator, refrigerant conveying means having one end thereof disposed below the level of liquid refrigerant 95

100 in said first named evaporator and having its other end extending above the level of liquid refrigerant, a Venturi device within a portion of said conduit, the end of said refrigerant conveying means above the level of liquid refrigerant in said first named evaporator being associated with said Venturi device, and said Venturi device being rendered effective by operations of said refrigerant liquefying and circulating unit for transferring liquid refrigerant from said first named evaporator to said second named evaporator.

105 110 115 120 125

10. A refrigerating apparatus comprising in combination, a compartment having an evaporator disposed therein, a second compartment also having an evaporator disposed therein and located above the evaporator in the first named compartment, a refrigerant liquefying and circulating unit having a liquid refrigerant supply connection with the first named evaporator and a gaseous refrigerant connection with the second named evaporator, means for maintaining a predetermined quantity of liquid refrigerant in said first named evaporator, a conduit extending from said first named compartment to said second named compartment and having one of its ends communicating with the first named evaporator above the level of liquid refrigerant there- 130
